(57) **CLAIM**

The ornamental design for a makeup applicator, as shown and described.

DESCRIPTION

FIG. 1 is a top plan view of a makeup applicator showing my new design;

FIG. 2 is a front elevational view thereof, the rear elevational view being a mirror image thereof;

FIG. 3 is a bottom view thereof;

FIG. 4 is a left-side elevational view thereof, the right-side elevational view being a mirror image thereof;

FIG. 5 is an isometric view thereof; and,

FIG. 6 is a perspective view of the makeup applicator shown in an environment of use.

The broken lines represent environmental structure and form no part of the claimed design.

1 Claim, 2 Drawing Sheets
